UNITED STATES PATENT OFFICE.

ALBERT J. HARMS, OF VICTORIA, ILLINOIS.

SUPPORT FOR RAILWAY-RAILS.

No. 867,363.

Specification of Letters Patent.

Patented Oct. 1, 1907.

Application filed August 17, 1906. Serial No. 330,938.

To all whom it may concern:

Be it known that I, ALBERT J. HARMS, a citizen of the United States, residing at Victoria, in the county of Knox and State of Illinois, have invented certain new and useful Improvements in Supports for Railway-Rails, of which I do declare the following to be a full, clear, and exact description, reference being had to the accompanying drawing, forming part of this specification.

10 The object of this invention is to provide a simple, durable and effective construction of support for railway rails, and the invention consists in the features of novelty hereinafter described, illustrated in the accompanying drawing and particularly pointed out in the 15 claims at the end of this specification.

Figure 1 is a plan view (parts being shown broken away) of a portion of a railway track having my invention applied thereto. Fig. 2 is a vertical section on line 2-2 of Fig. 1. Fig. 3 is an enlarged view in vertical section on line 3-3 of Fig. 1. Fig. 4 is a detail plan view showing a portion of one of the metal ties. Fig. 5 is a view in side elevation of the metal tie plate.

In the form of the invention illustrated in the accompanying drawing, the tie A is preferably formed of an I-beam, the broad base a of which will rest upon the roadbed in the usual manner. Upon the flanged head a' of the tie are mounted the tie plates B. Each of these tie plates B comprises a base portion adapted to extend across the head a' of the tie, and from the opposite edges 30 of each tie plate rises an inwardly turned flange b adapted to engage with the base flanges c of the railway rail C. From the edges of each tie plate B, opposite the reverted flanges b , extend the downwardly bent webs or parts b^2 that may project down a sufficient distance to engage or 35 rest upon the base flanges a of the tie A, and these depending portions b^2 project beneath the head flanges a' of the tie A and securely interlock the tie plate therewith.

By reference more particularly to Figs. 1 and 4 of the 40 drawing, it will be seen that the top flanges a' of the tie are formed with notches or cut-away spaces a^2 and, when the tie plates are in position for use, the inner portions of the downwardly extending parts b^2 of each tie plate sit within these notches a^2 and thus guard the tie plate 45 against lateral movement.

If desired, each tie plate may be formed with laterally extending ears b^4 having holes therein adapted to register with holes a^3 formed in the top flanges of the tie A and to receive through bolts for more securely holding the tie plates in position. When the tie plates are 50 in position for use, retaining rods or fasteners E may be employed, these fasteners extending diagonally beneath and across the ties and having upwardly bent portions, the ends c of which are bent over the flanges b of the tie plates, and these fasteners are particularly desirable if the ears b^4 are not employed.

In order to effect the insulation of the rail from the tie, a sheet D of indurated fiber or like insulating material is interposed between each of the tie plates and the rail, this sheet D being cut to a shape corresponding to that of the tie plate and having flanges that correspond with the flanges b of the tie plate.

In placing the tie plates in position for use, the rail C is elevated, as shown at the right-hand side of Fig. 2 of the drawing; and the tie plate B with the insulating sheet D therein is placed beneath the rail C in substantially the position shown in Figs. 1 and 2, so that the base flanges c of the rail may pass between the flanges b of the tie plate. The tie-plate B is then turned from the position shown at the right-hand side of Fig. 1, to the position shown at the left-hand side of Fig. 1, and this turning of the tie plate not only causes the flanges b to overlap the base flanges c of the rail C, but also causes the depending portions b^2 of the tie plate to pass within the notches a^2 of the tie and to engage with the top flanges a' 75 of the tie. When the tie plate has been thus set in position for use, retaining bolts may be passed through the holes b^1 of the tie plate and tie respectively, or, retaining rods E may be employed for holding the tie plates in position, or, both the bolts and retaining rods may be 80 used, if desired.

It is obvious that the precise details of construction above set out may be varied without departing from the spirit of the invention, and features of the invention may be employed without its adoption as an entirety. 85

I do not wish to be understood as claiming in this application any features of construction set forth and claimed in a companion application filed by me of even date herewith.

Having thus described my invention, what I claim as 90 new, and desire to secure by Letters Patent, is:—

1. A support for railway rails comprising a metal tie having a slotted flanged head, tie plates resting upon said head and arranged to extend beneath and across the base flanges of the rails, each of said tie plates having at its 95 opposite sides upturned flanges to engage the base flanges of the rail and each of said tie plates having a downwardly extending part adapted to engage and pass beneath the slotted flanged head of the tie.

2. A support for railway rails comprising a tie having 100 a flanged head slotted upon opposite sides and a tie plate upwardly flanged to engage the base of the rail and arranged to extend beneath said rail base and having downwardly and inwardly projecting flanges upon opposite sides adapted to enter the slots of the tie and pass beneath the flanged head thereof.

3. A support for railway rails comprising a tie plate having at each end an upwardly and inwardly turned flange to engage the base of the rail, said flanges being arranged at opposite sides of the tie plate and having laterally projecting ears extending in the plane of the tie plate between the upturned flanges thereof. 110

ALBERT J. HARMS.
